UNITED STATES PATENT OFFICE.

JAMES ROBERT STEELE, OF OWEGO, NEW YORK.

ANTICREEPER.

1,249,687.

Specification of Letters Patent. Patented Dec. 11, 1917.

Application filed June 9, 1917. Serial No. 173,759.

To all whom it may concern:

Be it known that I, JAMES ROBERT STEELE, a citizen of the United States, and resident of Owego, in the county of Tioga and State of New York, have invented a new and useful Anticreeper, of which the following is a specification.

The invention is an improvement in anticreepers and its object to guard against loosening of the device as the result of side thrust in frozen ground, or under other conditions producing a like effect. The construction herein claimed is more particularly a development of the type of anticreeper constituting the subject-matter of my copending application, Serial No. 87,165, filed April 18, 1917.

In the accompanying drawings:

Figure 1 is a cross-section through the rail, showing a portion of the tie in elevation and the anti-creeper applied to the rail-base; and

Fig. 2 is a vertical section on the line 2--2 of Fig. 1.

The yoke 1, which may be economically manufactured by cutting it out of flat steel, comprises a transverse, under-rail body 4 and inturned-ends 2 and 3 which hook over the sides of the rail base. The body 1 is dropped sufficiently below the position of the rail base to allow for clearance and wedging room, and, for further clearance in applying the yoke onto the rail sidewise of the latter, the interior space is extended outward below the hook end 2, such extension being designated 12*. By engaging this end over the rail base first the yoke may be tilted and shifted laterally onto the rail in a manner which will be readily understood. Beneath the opposite end 3 there is preferably an abutment face 10 to bear against the edge of the rail base at that side.

As in my prior application, the top of the body 4 is preferably inclined lengthwise of the yoke and transversely of the rail to form a wedge-way, which slopes upward toward the end 2, beneath which is the end clearance space. Upon this wedge-way and in the space between the same and the rail-base there operates a relatively short wedge 5 having a horizontal upper face and an inclined lower face and lateral portions 6 which project beyond the sides of

the yoke and downwardly to embrace the same. When the device is put upon the rail, the wedge is disposed at the lower end of the wedge-way adjacent the hook end 3, and after the yoke is on it is driven toward the end 2, thereby throwing the body 4 in tension and elastically gripping the anticreeper upon the rail base. The wedge may be provided with a flexible locking rod cooperating with a hole in the yoke, as in my other case, but since the wedge is self-holding without this provision it has been omitted in the present construction. The security of this holding may be increased by forming the wedge with a substantially square or sharp corner 11 at the rear end of its inclined bottom face, such corner opposing any rearward movement of the wedge by tending to dig into the slightly bowed wedge-way.

The particular improvement of the present case consists in the provision of an inclined camming face 12 on the under side of the hook end 2 having the clearance extension 12*, this face sloping reversely to the wedge-way and at a steeper angle than the same, and steeper also than the slope of the rail-base, with which it contacts at the extreme edge. That is to say, when the yoke is fully seated with the end 3 in position to abut against its edge of the rail base and the other end 2 is shifted outward from its initial applying position, the under face 12 is not parallel with the top of the rail flange but slopes upward in the direction of the web of the rail more abruptly than the flange surface, with which it forms an acute angle. The effect of this face is to cause any tendency of the device to shift in the direction from 2 to 3 to increase the tightness of the grip, owing to the fact that if such motion occurred the camming face would rise up on the rail-base at a rate which would cause the anti-creeper to bear more forcibly against the bottom of the rail rather than to descend away from the same. Accordingly side thrust of the rail toward the end 2 when the anti-creeper is held in frozen ground cannot loosen the device.

While I prefer to use the separate driven wedge characteristic of my prior invention, it will be understood that the present invention is not in all instances limited ther-

to and that other means may be employed for securing the bearing upon the bottom of the rail at a point intermediate the hook ends so as to tension the yoke and cause it to grip the rail base.

5 What I claim as new is:

1. In an anti-creeper, a yoke having in-turned ends to hook over the rail base, the yoke being adapted to be tilted and shifted transversely onto the rail base and the first applied having a clearance extension beneath it, the under side of said end being formed as a camming surface adapted to slope at a steeper angle than the top of the rail flange, which it engages at the extreme edge.
2. An anti-creeper comprising an elastic yoke having in-turned ends to hook over the rail base and intermediate means to bear upon the bottom of the same so as to tension the yoke and cause it to grip the rail, the yoke being adapted to be tilted and shifted transversely onto the rail base and the end first applied having a clearance extension beneath it, the under side of said end being formed as a camming surface adapted to slope at a steeper angle than the top of the rail flange, which it engages at the extreme edge.
3. An anti-creeper comprising a yoke having in-turned ends to hook over the rail-base and a transverse body portion dropped below the position of the rail-base and having an inclined wedge-way sloping lengthwise of the yoke and transversely with respect to the rail, and a wedge operative upon said wedge-way, the yoke having a clearance extension of its interior space below the hook end toward which the wedge is driven and said end having a camming under surface to bear upon the upper edge of the rail-base,

which surface is inclined reversely to the wedge-way and at a relatively steep angle.

4. An anti-creeper comprising a yoke having in-turned ends to hook over the rail-base and a transverse body portion dropped below the position of the rail-base, wedging means operative between said body portion and the rail-base, the yoke being further provided with a clearance extension of its interior space below one hook end and said end having a camming under surface which bears upon the rail-base at the edge and is inclined at a steeper angle than the top of the rail-base so that any tendency of the yoke to shift laterally upon the rail increases the tightness with which it is gripped thereto.

5. An anti-creeper comprising a yoke having in-turned ends and a dropped body with a wedge-way extending longitudinally on the body and a clearance extension of the interior space below the hook end adjacent the higher end of the wedge-way, said hook end having a camming under surface inclined at a relatively steep angle to bear upon the rail at the edge, and a short wedge operative in the space between the yoke body and rail-base transversely of the rail.

6. An anti-creeper comprising a yoke having hook ends and interior clearance and wedging room, and its body being formed with a wedge-way sloping lengthwise of the yoke and transversely with respect to the rail, and a relatively short wedge adapted to be driven on said wedge-way in the space between the same and the bottom of the rail and having a substantially square corner at the rear end to cooperate with the wedge-way to prevent retreat of the wedge.

JAMES ROBERT STEELE.
